UNITED STATES PATENT OFFICE.

BRUNO REICHELT, OF NEWARK, NEW JERSEY, ASSIGNOR TO BETA FERTILIZER COMPANY, OF NEWARK, NEW JERSEY.

FERTILIZER.

13,540.

Specification of Reissued Letters Patent. Reissued Mar. 4, 1913.

No Drawing. Original No. 943,460, dated December 14, 1909, Serial No. 488,006. Application for reissue filed May 19, 1911. Serial No. 628,315.

To all whom it may concern:

Be it known that I, BRUNO REICHELT, a citizen of the United States, residing at Newark, in the county of Essex and State 5 of New Jersey, have invented certain new and useful Improvements in Fertilizers, of which the following is a specification.

This invention relates to fertilizers.

One object of the invention is to provide 10 a fertilizer embodying properties capable of quickly enriching the roots of crops or vegetables to insure expeditious growth of the same.

Another object is to provide a fertilizer 15 possessing such characteristics that it will not form into lumps but will retain the condition requisite to preventing the clogging of the fertilizing machinery and particularly provide for a "spray-like" or powdered feed thereof to the earth.

In compounding my fertilizer I preferably employ talc rock containing potash and lime as a filler, the same being preferably deprived of all moisture and ground by 25 suitable machinery into a dry finely powdered condition. Under certain conditions I may employ two hundred pounds of crushed or powdered talc containing approximately six per cent. of potash and approximately four per cent. of lime to which I may add 100 pounds of ground oyster shells containing approximately four per cent. of ammonia and finally I add 40 pounds of ground phosphate rock containing 30 approximately 68 per cent. of phosphorus thoroughly mixing all of said ingredients in any suitable manner.

Talc is naturally slippery and will prevent the adherence of particles thereof or

the formation of lumps in the mixture. 40 Moreover, the talc will not only insure the maintenance of the required powdered condition of the mixture, but it will provide for a "spray-like" flow of the mixture when discharged from a fertilizer machine thereby insuring an effectual impregnation of all parts of the earth over which the fertilizer is distributed. 45

My improved fertilizer has quick action upon the roots of crops incident to a high 50 character of enriching properties and the more it is used year after year, the richer becomes the ground.

What is claimed is:—

1. A fertilizer consisting of crushed talc 55 containing potash, and lime, mixed with ground oyster shells containing ammonia and ground phosphate rock substantially as described and for the purposes specified.

2. A fertilizer comprising crushed talc 60 and ground oyster shells.

3. A fertilizer comprising crushed talc, ground oyster shells and ground phosphate rock.

4. A fertilizer comprising crushed talc, 65 ground oyster shells and phosphate.

5. A fertilizer comprising a mixture having crushed talc as a filler.

6. A fertilizer comprising crushed talc, 70 and a nitrogenous compound.

7. A fertilizer comprising crushed talc, a nitrogenous compound, and phosphate.

In testimony whereof I affix my signature in the presence of two witnesses.

BRUNO REICHELT.

Witnesses:

WILLIAM HILL,
HENRY JOS. AUTH.
